UNITED STATES PATENT OFFICE.

CORNELIUS HENRY VANDONK, OF WELLS, MICHIGAN.

CAR-STAKE AND POCKET.

1,074,668.

Specification of Letters Patent.

Patented Oct. 7, 1913.

Application filed March 3, 1913. Serial No. 751,846.

To all whom it may concern:

Be it known that I, CORNELIUS H. VANDONK, a citizen of the United States, residing at Wells, in the county of Delta and 5 State of Michigan, have invented a new and useful Improvement in Car-Stakes and Pockets, of which the following is a specification.

This invention is an improvement upon 10 patent granted me April 30, 1912, Number 1,024,608.

One object of the invention is to provide a device of this kind in which the pocket will not project beneath the car sill thereby 15 adapting the same for use with certain types of cars with which it is not convenient to have the operating shaft or any part of the pocket extend beneath the car.

The invention also consists of a number 20 of improvements in mounting the various parts, as well as minor improvements in the construction of the pocket itself, all of which will be hereafter explained in detail, pointed out in the claims and shown in the accompanying drawings, in which:

Figure 1 is a front elevation. Fig. 2 is a side elevation. Fig. 3 is a vertical section through the pocket the door being shown in open position. Fig. 4 is a longitudinal section through a bushing carrying certain operating segments. Fig. 5 is a sectional detail view illustrating the construction of a two part bushing for an operating shaft, taken on line 5—5 of Fig. 2. Fig. 6 is a detail sectional view illustrating the reinforcement of a hook. Fig. 7 is a side elevation of a bushing especially adapted for use with a modified form of pocket. Fig. 8 is a side elevation of such modified construction of 40 pocket. Fig. 9 is a front view of said pocket, the door and operating means being removed.

The operation of this pocket is substantially the same as that of the pocket set forth 45 in the patent referred to, and the said pocket is designed to hold a stake constructed in accordance with the one shown in my previous patent.

In the above described drawings, 1 represents 50 the pocket and it will be noted that the rear wall 2 of the pocket and the bottom 3 slope downwardly and outwardly, so that when the front door swings downwardly into the position shown in Fig. 3 the stake 55 will readily fall from the pocket thereby avoiding all danger of the stake becoming

jammed in said pocket. The door 4 is provided with a hook member 5, and said hook member is reinforced and strengthened by a side web 6, said web serving also as a side wall 60 of a pocket and preventing the parts becoming accidentally unhooked by lateral displacement of the shoulder of a pivoted locking member 7 which is engaged by the hook 5 when the door is in closed position. This 65 locking member corresponds to a pivoted arm shown in my previous patent. The shape of this part has been changed and I have also improved the manner of mounting the same upon the pocket. This improvement consists in forming upon the back plate of the pocket outwardly extending lugs 8 slightly spaced from the pocket and the locking members 7, there being one upon each side of the pocket, are pivoted between 70 75 said lugs and the sides of the pocket, respectively. By means of these lugs and the reinforcement of the hook members 5, the locking member 7 is limited to movement in a vertical plane only. This, of course increases 80 the movements of the parts in the manner designed, and also decreases the likelihood of the locking members being accidentally twisted or torn from their proper positions. Below the bottom 3, the sides of 85 the pocket are extended downwardly forming parallel brackets 9 and in said brackets I journal a sleeve 10, one end of which carries an integral segment 11 and the opposite end is squared and upon said squared portion is fitted a similar segment 12. These 90 segments are also provided with integral arms 13, the extreme ends of which are slightly curved to coöperate with the slightly curved face of an operating point 95 14 carried by each locking member 7. The door is also hinged by a suitable pintle 15, which passes through said brackets and suitable downwardly extending lugs 16 and said door is provided with a suitable spring 17, 100 which throws the same downwardly and holds it in position beneath the pocket as shown in Fig. 3, thereby making it absolutely certain that the lower end of the stake will not catch or hang upon any portion of 105 the door but would clear the pocket and all parts attached thereto. Journaled in the brackets 9, I also arrange a two part bushing 18, said bushing being divided into two half sections, the inner end of each of which 110 is partly cut-away leaving interlocking hook members 19. The sleeve 18 like the sleeve

10 has a squared bore and is adapted to receive an operating shaft 20, similar to the one shown in my previous patent. The sleeve 18 also carries segments 21, which are adapted to mesh with the segments 11 and 12. These intermeshing segments also carry at an end of the toothed sections blunt teeth or shoulders 22, which when they engage each other act as stops and limit turning movement of the intermeshing segments. 10 This prevents the segments being turned into such position that the teeth of one segment will clear those of the other.

It will be obvious from the above description 15 and the drawings that when the shaft 20 is rotated the gears 21 will be rotated from right to left, and the gears 11 and 12 from left to right, thereby swinging the arms 13 upwardly so that they will free 20 the tapering points 14 of the locking members 7, thereby permitting said locking members to drop into a substantially vertical position, thus withdrawing the shoulders 7^a from the hook members 5, and permitting 25 the spring 17 to throw the door 4 into open position.

In order to adapt the pocket above described to a certain type of car in which it is not desirable for the brackets 9 or the 30 operating shaft 20 to extend beneath the car sill I provide a form of pocket 23 shown in Figs. 8 and 9 and which is provided with substantially the same parts as the pocket 4 with the exception that the depending brackets 24 do not extend downwardly beneath the car sill as do the brackets 9. This of 35 course reduces the bearing surface of the brackets and consequently a divided bushing 25 similar to the sleeve or bushing 18 is 40 mounted in suitable bearings 26 formed in the brackets 24 and these bushings instead of being provided with segments or mutilated gears carry directly arms 27 which correspond in size and shape to the arms 45 13, and coöperate in the same way with the tapering points 14 of the locking members 7. The bushing 25 also carries at each end suitable stops 28 adapted to engage the locking members 7 and limit relative movement 50 of said arm and said hook members. It will be noted that in this last described construction the under-hanging of the parts is entirely avoided.

What I claim is:

- 55 1. A stake pocket having a forwardly inclined rear wall and a forwardly and downwardly inclined bottom, the side walls of said pocket extending downwardly below said pocket, a spring pressed door adapted 60 to close the front of the pocket, means for locking said door in closed position and operating means journaled in said side walls and below said bottom for the purpose of releasing said door.
- 65 2. The combination with a stake pocket

having depending side members, a divided bushing journaled in said depending members, said bushing being formed in interlocking half sections, toothed segments carried at an end of each section, an operating shaft extending through said bushing, a sleeve journaled in said depending members, segments carried by said sleeve and meshing with the segments of the bushing, a hinged door for said pocket, pivoted locking members carried by the sides of the pocket, hook members carried by the door and adapted to engage portions of said locking members, and arms carried by the second mentioned segments and adapted to engage 80 said pivoted locking members for the purpose of holding them in locking position relative to the hook members carried by the door.

3. A car stake comprising a front door 85 adapted to swing outwardly and downwardly, hook members carried by the free end of said door and adapted to overlap the sides of the pocket, pivoted locking members carried by said sides, said locking members having shoulders adapted to be engaged by said hook members, said locking members having curved side faces adjacent their free ends, a rotatable sleeve journaled below said pocket, arms carried by said sleeve 95 having curved end portions adapted to engage the curved faces of said locking members, and means for rotating said sleeve.

4. The combination with a pocket, a spring pressed door adapted to close the 100 front of the pocket, and to swing downwardly beneath the pocket, hook members carried by said door and adapted to overlap the sides of the pocket, pivoted locking members carried by the sides of the pocket 105 and adapted to be engaged by said hook members, a rotatable sleeve journaled beneath said pocket, means carried by said sleeve for engaging said locking members and holding them in engagement with the 110 hook members, means for rotating said sleeve, and a stop carried by said sleeve and adapted to limit rotation of the sleeve in one direction.

5. A car stake pocket comprising an 115 integral back plate, side and bottom members, a door adapted to close the front of said pocket and adapted to swing downwardly beneath the pocket, lugs carried by the said back plate, said lugs being arranged respectively upon opposite sides of the pocket, and spaced therefrom, locking members pivoted between said lugs and the sides of the pocket, and hook members carried by the door and adapted to overlap the sides of the pocket 120 and to engage portions of said locking members, said hook members being provided with a lateral web adapted to partially inclose portions of the said locking members, as and for the purpose set forth.

6. In a device of the kind described, a bushing divided into two half sections, the inner ends of said sections being adapted to interlock one of said sections having a 5 segmental gear formed thereupon, the other section having a segmental gear fixed thereupon, a car stake pocket, means depending from said pocket adapted to form bearings for said bushing, and means operated by rotation of said bushing for locking and un- 10 locking said pocket.
